UNITED STATES PATENT OFFICE.

HENRY L. WARD, OF CHICAGO, ILLINOIS, ASSIGNOR TO WESTERN ELECTRIC COMPANY, INCORPORATED, OF NEW YORK, N. Y., A CORPORATION OF NEW YORK.

OPERATION OF ELECTROLYTIC CELLS.

No Drawing. Application filed March 4, 1922. Serial No. 541,203.

To all whom it may concern:

Be it known that I, HENRY L. WARD, a citizen of the United States, residing at Chicago, in the county of Cook and State of Illinois, have invented certain new and useful Improvements in the Operation of Electrolytic Cells, of which the following is a full, clear, concise, and exact description.

10 This invention relates to improvements in the operation of electrolytic cells, and more particularly to the prevention of acid spray in electrolytic solutions.

In the operation of certain electrolytic cells and particularly those used for the electrolytic recovery of copper from pickling solutions in which insoluble anodes are used, the liberation of fine bubbles of oxygen gas in the solution causes a disagreeable acid spray to be formed.

It has been found, however, that if these finer bubbles of oxygen or other gas can be caused to coalesce into larger bubbles, the spray will be prevented from escaping 25 into the atmosphere adjacent the cells to the discomfort of those working in the vicinity.

In accordance with the general features 30 of this invention, the finer bubbles generated in the action of the electrolyte are caused to coalesce into larger bubbles. It has been found that the coalescence of the smaller bubbles may be brought about by applying to the surface of the electrolyte 35 a finely divided buoyant material. For this purpose finely divided cork or cork granules have been found to be particularly satisfactory, and a layer of granular

cork on the surface of the solution will prevent the acid spray being liberated in 40 the vicinity of the cell.

It has also been found that impregnation of the cork with some chemically inactive moisture-proofing material, such as paraffin or linseed oil, will prevent the cork from 45 becoming water-logged and sinking to the bottom of the solution.

What is claimed is:

1. The method of preventing disagreeable acid spray in the vicinity of electrolytic cells, which consists in applying a 50 layer of finely divided cork treated with chemically inactive, moisture-proof compound to the surface of the electrolyte.

2. The method of preventing disagreeable acid spray in the vicinity of electrolytic cells, which consists in applying a 55 layer of granular cork treated with paraffin to the surface of the electrolyte.

3. The method of preventing disagreeable acid spray in the vicinity of electrolytic cells which consists in applying a 60 layer of granular cork to the surface of the electrolyte, each granule being impregnated with a chemically inactive moisture proof 65 material.

4. The method of preventing disagreeable acid spray in the vicinity of electrolytic cells which consists in applying a 70 layer of granular cork to the surface of the electrolyte, each granule of the cork being impregnated with paraffin.

In witness whereof, I hereunto subscribe my name this 25th day of February A. D. 1922.

HENRY L. WARD.
